APPARATUS AND METHOD FOR INSERTING INDICIA IN SOAP

James Garvey, P.O. Box 669, Station A, Vancouver,
British Columbia, Canada

Filed Sept. 11, 1961, Ser. No. 137,293

12 Claims. (Cl. 264—171)

This invention relates to method and apparatus for inserting indicia in bars of soap so as to produce a compound column of soap comprising body soap compacted around and bonded to a rod of indicia soap.

In United States Patent 2,296,842, issued September 29, 1942, to James Garvey et al., for an invention entitled Method of and Apparatus for Inserting Indicia in Soap, there was disclosed and claimed a method by which a so-called "rod" of indicia is inserted in the center of a column of soap issuing from the exit end of a finishing plodder. The method and apparatus disclosed and claimed in this application relate to certain improvements on the invention disclosed in the said prior patent.

Among the difficulties encountered in satisfactory introduction of an indicia rod into a column of soap in a finishing plodder are those which result in so-called "pinch-off" of the indicia rod in the region of the nozzle end of the plodder where the pressure of the "body soap" is greatest. It appears that when an indicia rod is introduced into body soap in the nozzle portion of a plodder of otherwise conventional design the substantial pressures exerted on the body soap by the plodder screw cause it, in certain circumstances, to compact very tightly on the region of the end of the indicia rod guide tube so as to "pinch-off" the indicia rod itself and thus yield a column of soap having gaps in the indicia portion, or at least distortions therein. Another problem is that which has attended the formation of a completely satisfactory bond between the body soap and the rod. While with many soaps it is possible, by very careful control of operating conditions, to effect a satisfactory bond between the body soap and the indicia rod as a result of the pressure and temperature generated within the plodder itself, operations on a commercial scale would be much simplified if some agency in addition to inherent temperature and pressure within the plodder could be relied upon to ensure a full satisfactory bond. Finally, I have found it advantageous and indeed necessary, so far as concerns commercial operation of the invention, to be able to control during operation of the plodder both the radial position of the indicia rod, as it is introduced into the body soap, and the precise point within the plodder at which the body soap is allowed to surround and grip the indicia rod. These requirements arise as a result of the necessity of adjusting orientation of the indicia within the body soap, and that of ensuring the best possible compacting of the body soap around the indicia rod, consistent with the absence of pinch-off effect. It is an object of the method and apparatus herein disclosed to provide means by which "pinch-off" can be avoided and the other desiderata mentioned above obtained.

The novel method which forms the basis of my invention comprises the steps of coating the indicia rod with a bonding solution and simultaneously advancing both it and the body soap through the cylinder of the plodder while preventing contact therebetween. In the nozzle portion of the plodder a region of reduced pressure is produced in the body soap, and within this region the body soap is allowed to come into contact with the indicia rod, drawing it automatically into the advancing column of body soap so that the latter is formed around the rod. Upon further advance of the compound column of soap thus formed the body soap is compressed about the rod

2

and is firmly bonded thereto. In order to carry out this method my invention contemplates the provision of suitable apparatus for precoating the indicia rod with bonding solution, and also effecting reduction of pressure in the nozzle portion of the plodder, as aforesaid, for facilitating smooth drawing in of the rod into the body soap and for making adjustments in both the radial position of the indicia rod, and the point at which it first comes into contact with the body soap.

The present invention will be described in more detail with reference to the following drawings in which:

FIGURE 1 is an elevation (partially in section) of apparatus for carrying out the method according to the present invention;

FIGURE 2 is a cross-sectional view of the fog coating apparatus shown in FIGURE 1;

FIGURE 3 is a cross-sectional view of the indicia rod support shown in FIGURE 2 taken along the line 3—3 thereon;

FIGURE 4 is a cross-sectional view of the indicia rod guide tube taken along the line 4—4 of FIGURE 1;

FIGURE 5 is a pictorial view of a guide die;

FIGURE 6 is a pictorial view of a shroud designed to be mounted in the nozzle portion of the plodder so as to create a region of reduced pressure therein;

FIGURE 7 is a center sectional view of apparatus for adjusting the guide tube along and about its longitudinal axis, and

FIGURE 8 is a cross-sectional view taken along the line 8—8 of FIGURE 7.

Referring now to the drawings and particularly to FIGURE 1, there is shown an indicia soap rod 1 issuing from the output nozzle 2 of a plodder adapted to produce indicia soap rod, the design of which does not form part of the present invention and will not therefore be described in detail. The indicia soap rod then passes from left to right through a fog coating apparatus generally indicated at 3 which rests on a vertically adjustable base 4. On leaving the fog coating apparatus, the rod passes through a guide tube generally indicated at 5 from its entry end 6 to its exit end generally designated at 7. A substantial portion of the guide tube 5 is disposed in a hollow shaft 8 of a rotatable plodder screw 9 which is mounted in a finishing plodder 10 having an inlet 11, a cylinder portion 11a accommodating the screw, and nozzle portion 11b terminating in an outlet generally designated at 12. When the plodder screw is rotated, body soap which is introduced into the inlet 11 is mixed or "plodded" thoroughly so as to be physically worked, compacted and moved under increasing pressure through the cylinder and nozzle portions towards the outlet 12. The guide tube 5 is positioned in the hollow shaft 8 by means of a guide bearing 13 located at the forward end of the shaft. The guide bearing 13 permits the guide tube 5 to be moved longitudinally along, and to be rotated about, its axis, independent of the rotation of the plodder screw 9. Guide bearing 13 also provides a soap-tight seal preventing the entry of body soap into the hollow shaft from the plodder proper. The exit end 7 of the guide tube 5 extends in cantilever fashion beyond the bearing 13 into nozzle portion 11a of the plodder, toward plodder outlet 12.

Along the length of the guide tube means are provided for supporting the indicia soap rod from the entry end to the exit end of the tube. FIGURE 4 shows such a supporting means which, in this case, consists of a guide track 14 of substantially semi-circular cross-section so as to provide a tight engagement with the lower part of inner surface of the guide tube 5. A groove 15 is provided in the upper surface of track 14 so as to accommodate a given cross-section of indicia rod. The groove 15 must have sufficient depth so that the indicia

soap rod, which is preferably of non circular cross-section in order to facilitate control of its radial position, will not tend to rotate in the track.

The exit end 7 of the guide tube which extends beyond the guide bearing 13 terminates in a guide die 16 which is shown in more detail in FIGURE 5. The guide die is rigidly attached at its inner end by any suitable means to the end of the guide tube 5 and tapers gradually from this point to its free end 17. The inner surface of the free end 17 is adapted to conform very closely to the shape of the indicia soap rod 1 and the external surface of the free end follows the shape of the inner surface. Thus in the embodiment shown in the drawings the inner and outer surfaces of the end 17 are oval in shape to conform with rod 1. The resulting taper in the shape of the outer surface of the guide die facilitates the flow of body soap about the die and tends to ensure that the body soap will be brought in contact with substantially the entire periphery of the indicia soap rod as it leaves the free end 17 of the guide die. A series of longitudinal slots 18 through the guide die extend back from the free end 17. These slots have outwardly chamfered edges which facilitate the entry of the body soap into the slots and permit limited preliminary contact between the body soap and indicia soap rod within the die. The movement of the body soap and the contact between the body soap and the indicia rod through the slots 18 and beyond the free end 17 causes the indicia soap rod to be "drawn" from the guide tube 5 into the column of body soap as the latter moves forward. The slots 18 in the guide die 16 are designed to permit gradual application of the body soap pressure to the indicia soap rod, thereby reducing the tendency for "pinch-off" to occur in the region of the end 17.

In a finishing plodder of the type used in the apparatus here described the pressure exerted by the body soap in the nozzle portion of the plodder is extremely high. Since the free end 17 of the guide die is located in this region of high pressure, there is a tendency for the indicia rod as it enters the mass of body soap to be "pinched-off." One means of assisting in overcoming this difficulty is the provision of a pressure reducing member 19 which is adapted to be mounted in the nozzle of the plodder. This member has a passage 20 which extends between oppositely facing openings 21 and 22 which are positioned in planes perpendicular to the soap flow. While I do not wish to be bound by any theory concerning my invention, it appears that as a result of a reduced cross-sectional area of the passage 20, compared with that of the nozzle portion itself, the velocity of the body soap through the passage 20 is increased relative to that of the soap in the other parts of the nozzle and the pressure exerted by the body soap in the passage 20 is accordingly decreased. In one particular embodiment of my invention, the passage 20 is defined by a shroud 23 (in FIGURE 6). The shroud is positioned adjacent to the outlet of the plodder, in the nozzle portion thereof, by means of mounting lugs 24 which are affixed by means of mounting screws 25 to the walls of the plodder. The mounting lugs 24 are of "streamlined" generally oval cross-section as shown so as to facilitate movement of the soap therearound. To permit adjustment of the shroud in different portions along the longitudinal axis of the plodder, a series of mounting holes 26 is provided along the walls of the nozzle section. The mounting holes which are not in use are plugged by extra mounting screws 25 to prevent the escape of body soap from the plodder. The free end 17 of the guide die 16 is positioned in the passage defined by the shroud 23 so that the indicia soap rod first comes in contact with body soap in a region of reduced body soap pressure, thereby reducing the tendency for "pinch-off" to occur. The cross-sectional shape of the passage 20 is chosen to correspond generally with the

cross-sectional shape of the compound column of soap which will be extruded out of the outlet end of the plodder.

After the body soap with associated indicia rod has passed through the exit opening 22 of the passage 20 the soap is extruded through the outlet 12 of the finishing plodder. This outlet is of a standard type known in the prior art and consists of a forming plate 27 having the desired cross-sectional shape of the finished soap bar, followed by a soap bearing 28. After the soap has been shaped by the forming plate 27, it is polished by the soap bearing 28 and then passes through a thermostatically controlled electrical heater, 29, into an automatic cutter, which in turn feeds the cut soap bars into a "soap press" and a "wrapping machine" (not shown).

The fog coating apparatus designated generally at 3 in FIGURE 1 is shown in more detail in FIGURE 2. It consists of a container generally indicated at 30 including a bottom section 30a having an integrally mounted bowl 31 formed in its base. A unit generally indicated at 32, consisting of a centripetal impeller 33, and a centrifugal impeller 34 joined by a hollow shaft 35, is rotated by a rotating drive 36 which, in the embodiment shown, consists of a high speed electric motor positioned in the container by means of mounting brackets 37. Means generally indicated at 38 are provided for introducing a bonding solution into the container and for maintaining the surface of the solution at a predetermined level 39. In the particular embodiment illustrated this means consists of an inlet 40 below the level 39 and an over-flow outlet 41 above it. An inlet valve is provided to regulate the entry of liquid in accordance with the position of a float 43 which rests on the surface of the liquid. The sides of the bowl 31 have a height approximately equal to the position of the level 39 from the bottom of the bowl.

The centripetal impeller 33 is located within the bowl 31 and thus below the predetermined level 39. This impeller has a series of blades 44 which, when the impeller 33 is rotated in the bonding solution, move the solution radially inwards along the blades to the center, or output, 45 of the impeller. One end of the hollow shaft 35 is directly connected to this output of the impeller so that the bonding solution is driven up the hollow shaft 35 to the level of the centrifugal impeller 34 which is rotating above the predetermined liquid level 39. The bonding solution is fed to the input or hub 46 of the centrifugal impeller 34 through orifices 47 in the sides of the hollow shaft 35. A series of blades 48 which radiate from the hub of the centrifugal impeller move the solution radially outwards, away from the hub, and vertically upwards. The bonding solution leaves the centrifugal impeller in the form of small droplets which may be carried upwards by the vertical movement of air resulting from the rotation of the centrifugal impeller. The larger and heavier of these droplets fall downward and return to the mass of liquid in the container 30, while the smaller and lighter droplets are carried upwards by the air current. The container 30 includes a plastic extension element 49 which rests on an annular bearing surface 50 formed in the upper edge of the bottom section 30a and held thereon by means of releasable clamps 51. A cover generally indicated at 52 having an open cylindrical section 53 adapted to slide in telescoping fashion in the extension section 49 and having a dome shaped closure section 54 is also formed from a plastic material. Diametrically opposed apertures 55 and 56 are formed in the cylindrical walls 53. Spanning the space between the apertures 55 and 56 across the diameter of the container is a support 57 upon which the indicia soap rod 1 (shown in FIGURE 1) rests as it traverses the fog coating apparatus by entering the aperture 55 and exiting by the aperture 56. The support 57 is formed from a plastic tube having a plurality of slots 58 removed from its surface and leaving a series of spaced ribs 59 supported by longitudinal stringers 60 (as shown more clearly in FIGURE 3). The inner edges of the

ribs 59 are chamfered to reduce the effect of friction as the indicia soap rod slides over them. To ensure that the indicia rod receives an adequate, but not excessive, fog coating the position of the support 57 relative to the predetermined level 39 of bonding solution may be adjusted by sliding telescopically the cover 52 into or out of the extension 49. As the support 57 is moved farther away from the bonding solution the fog produced by the centrifugal impeller 34 becomes less dense and is composed of smaller droplets.

A plurality of air inlet ports 61 are provided in the sides of container 30a. Through these ports air is drawn into the stream of upwardly moving bonding solution droplets. The escape of this air from the fog coating apparatus is controlled by means of a vent 62 located in the domed closure 54 of the cover. The vent consists of an inner cylindrical member 63 formed integrally in the center of domed closure 54. A series of holes 64 are drilled through the inner member. A cover member 65 is rotatably mounted by means of a pivot 66 on the inner member. The cover member has a series of holes 67 which can by rotation be aligned with the holes 64, or part of them. By the adjustment of these vent openings another means is provided for regulating the amount of bonding solution fog deposited on the indicia soap rod as it passes through the coating apparatus.

It has been found advantageous when inserting indicia in soap to provide apparatus for adjusting the position of the guide tube 5 along and about its longitudinal axis while the plodder is in operation. The provision of an axial adjustment of the guide tubes facilitates the positioning of the free end of the guide die within the passage 20 in the pressure reducing member 19. By examining the soap extruded from the outlet 12 of the plodder it is possible for an operator to note the occurrence of any tendency towards a "pinch-off" condition. The axial movement of the guide die relative to the passage permits correction of this condition without the necessity for stopping the plodder. Another problem sometimes encountered results from a slight rotation of the indicia soap rod so that the indicia appearing in the extruded column of soap is not correctly oriented. Thus, if the indicia rod 1 shown as having an oval cross-section in FIGURE 4 were to become slightly rotated about its longitudinal axis, the result would become evident in the finished bars of soap cut from the column since, for instance, the axes of the oval would not be parallel to the sides of the bar. To compensate for this source of error, apparatus is provided according to the present invention for rotating the guide tube, and consequently the indicia rod, about its longitudinal axis, without stopping the operation of the plodder. As was discussed in relation to the axial correction, the amount of radial correction required may be determined from an examination of the soap output from the plodder.

The apparatus for carrying out the longitudinal and radial adjustment of the guide tube along and about its longitudinal axis is shown in FIGURE 1 generally by reference numeral 63, but will be described in more detail with reference to FIGURES 7 and 8. The walls of the guide tube 5 at its entry end 6 are outwardly flared. A gripping assembly generally indicated at 69 is provided for releasably engaging the guide tube about its flared entry end. The gripping assembly 69 comprises a hollow cylindrical member 70 having an outwardly directed annular plate 71 at its forward or inner end and having a center bore defined by outwardly tapering walls 72. The gripping assembly 69 further comprises a segmented collar 73 which is adapted to fit in the tapered annular space defined by the walls 72 of the member 70 and the outer surfaces of the guide tube 5. Screws 74 are provided for wedging each segment of the collar 73 firmly in place between the member 70 and the guide tube 5. Handles 75 are rigidly attached to the member 70 and permit the

manual rotation of the guide tube and indicia soap rod contained therein as will be explained hereunder.

Immediately forward of the member 70 and co-axial with the guide tube 5 is a hollow externally threaded shaft 76 having an annular plate end 77 which comes into facing engagement with the plate 71. The hollow shaft 76 and co-axial guide tube 5 pass through an aperture generally designated at 78 positioned in the center of a U-shaped fixed frame 79 which is rigidly attached to the rear wall 80 of the finishing plodder 10. Means 81 are provided to prevent rotation of the hollow shaft relative to the fixed frame 79. In a preferred embodiment of the invention the means 81 consists of an external key way 82 (see FIGURE 8) running the length of the threaded portion of the hollow shaft. A key 83 engages with both the fixed frame 79 and with key way 82 to prevent rotation of the hollow shaft.

Coupling means generally indicated at 84 are used for releasably clamping together member 70 and hollow shaft 76 at their annular plates 71 and 77 respectively. According to the embodiment of the invention illustrated the coupling means 84 consists of threaded shafts 85 and 86 which are rigidly attached to the plate 71 and extend through plate 77 in arcuate slots 87 and 88 respectively (see FIGURE 8). Nuts 89 and 90, having handles 100 are threaded on shafts 85 and 86 and, when tightened on the shaft, the member 70 is clamped to the hollow shaft 76, thus preventing the rotation of the gripping assembly, and consequently of the guide tube. However, when the coupling means 84 is released, it is possible by means of handles 75 to rotate the gripping assembly 69 and consequently, within the limits defined by the slots 87, 88, rotates the guide tube, since it is free to turn within the coaxial hollow shaft 76.

An adjustment wheel 91 has internal threads which engage with the external threads on the hollow shaft 76. The adjustment wheel is rotatably mounted to the fixed frame 79 by means of a bearing 92. The rotation of the adjustment wheel 91 advances or retracts the hollow shaft 76 relative to the wall 80 since the bearing 92 on fixed frame 79 prevents the adjustment wheel 91 from moving toward or away from the wall 90. Thus, by coupling the hollow shaft 76 to the gripping assembly 69 through the coupling means 84, it is possible to advance or retract the guide tube along its longitudinal axis to adjust the position of the free end 17 of guide die 16 in the passage 20 while the plodder is in operation. Because of the means 81 which prevent rotation of the hollow shaft relative to the fixed frame, the axial movement of the guide tube as a result of the rotation of adjustment wheel 91 is not attended by any rotation of the guide tube itself so that an independent and continuous axial adjustment of the guide tube within the plodder is provided. If it is desired to effect radial adjustment of the guide tube about its longitudinal axis without changing the axial adjustment, this may be accomplished by releasing the coupling means 84 and then rotating the gripping assembly 69 and guide tube 5 by means of handles 75.

What I claim as my invention is:

1. A method of forming in a finishing plodder a continuous column of soap consisting of body soap surrounding a rod of indicia, comprising the steps of: (a) coating said rod with a bonding solution; (b) simultaneously advancing the rod and body soap through the plodder while preventing contact therebetween until a predetermined location near the exit end of the plodder; (c) creating a region of reduced pressure on said body soap at said predetermined location; (d) permitting in said region at least partial contact between said body soap and said rod whereby the rod is automatically drawn into the mass of said body soap and the same is formed around the rod; (e) further advancing the rod and body soap past said region whereby the body soap is compressed about the rod and is bonded thereto.

2. A method as claimed in claim 1 comprising the step of adjusting the point at which, within said region, the whole periphery of said rod is permitted to come into contact with the body soap.

3. A method of producing a continuous compound column of soap comprising an indicia rod surrounded by body soap, said method including the steps of: (a) coating the rod with a bonding solution; (b) advancing said body soap along a path having an entry end and an exit end between which the body soap is physically worked and subjected to increasing pressure tending to compact the same; (c) simultaneously advancing said rod along said path so that it is surrounded by body soap but is out of contact therewith; (d) creating a region of reduced pressure within the mass of body soap adjacent the exit end of the path; (e) introducing the rod into said region and permitting the same to commence having contact, at all points about its periphery, with the body soap at a predetermined location therein, whereby the rod is drawn into the body soap as it moves along the path; (d) further advancing the compound column of soap thus formed so that the body soap is compacted about the rod and bonded thereto.

4. A method as claimed in claim 3 wherein before said location, and within said region, the body soap is permitted to have contact with a portion of the periphery of the rod.

5. A method as claimed in claim 3 comprising the further step of adjusting said location.

6. Apparatus for inserting indicia in soap so as to produce a compound column of soap consisting of body soap surrounding and bonded to a rod of indicia soap, said apparatus comprising: a plodder having a cylinder and nozzle portion contiguous with the cylinder at the forward end thereof; a helical screw disposed within the cylinder, said screw having its longitudinal axis concentric with that of the cylinder and adapted, when rotated, to cause compacting and movement of the body soap under increasing pressure through the cylinder and nozzle, said screw having a hollow shaft; means in said nozzle for establishing therein a region of reduced pressure; an indicia rod guide tube disposed along said axis in the hollow shaft so as to permit rotation relative thereto, said guide tube having an inlet end to which access can be obtained outside the plodder at the rear thereof, and an exit end located in said region.

7. Apparatus as claimed 6 comprising means for adjusting, when the plodder is in operation, the radial position about said axis of the exit end of the guide tube.

8. Apparatus as claimed in claim 6 comprising means for adjusting, when the plodder is in operation, the longitudinal position along said axis of the exit end of the guide tube.

9. Apparatus as claimed in claim 6 comprising means for adjusting, when the plodder is in operation, both the said radial and longitudinal positions of the exit end of the guide tube.

10. Apparatus as claimed in claim 6 wherein the said means for establishing a region of reduced pressure comprise a shroud mounted in said nozzle portion, said shroud comprising a tubular member defining a passage having entry and exit ends and a cross-section similar to that of the said compound column of soap, and wherein the exit end of the guide tube is located within said passage.

11. Apparatus as claimed in claim 6 wherein track means are disposed within the guide tube, said track means having a groove adapted for longitudinal sliding contact with at least a portion of the periphery of the indicia soap rod; and wherein the inner end of the guide tube comprises an indicia rod guide die having a passage therethrough adapted to conform closely with the periphery of the indicia soap rod, an outer surface of shape similar thereto, and longitudinal slots disposed around over the die, is shaped to conform with and receive the indicia soap rod passing therethrough and whereby contact the periphery thereof whereby the body soap, as it passes is permitted through said slots between the body soap surrounding the die and the indicia soap rod within it.

12. Apparatus as claimed in claim 6 wherein the exit end of the indicia rod guide tube is provided with longitudinal slots disposed around the periphery thereof.
